UNITED STATES PATENT OFFICE.

ALVIN M. CUSHING, OF SPRINGFIELD, MASSACHUSETTS.

SPRING-HEEL FOR BOOTS OR SHOES.

SPECIFICATION forming part of Letters Patent No. 554,988, dated February 18, 1896.

Application filed October 7, 1895. Serial No. 564,871. (No model.)

To all whom it may concern:

Be it known that I, ALVIN M. CUSHING, a citizen of the United States of America, residing at Springfield, in the county of Hampden and State of Massachusetts, have invented new and useful Improvements in Spring-Heels for Boots or Shoes, of which the following is a specification.

This invention relates to boots and shoes, and particularly to an improved construction of the heels thereof, the object being to provide improved spring devices for insertion in said heels; and the invention consists in the peculiar details of the construction of said heels and spring devices, all as hereinafter fully described, and more particularly pointed out in the claim.

In the drawings forming part of this specification, Figure 1 is a side elevation of the heel of a boot or shoe, partly in section and partly broken away, constructed and having spring-supporting devices applied thereto embodying my invention. Fig. 2 is a bottom plan view of the heel and spring devices, the outer lift of the heel being partly broken away. Figs. 3 to 5, inclusive, illustrate detail parts and are hereinafter fully described.

In the drawings, A indicates the heel of a boot or shoe which is constructed with a centrally-located chamber o therein, preferably of cylindrical form. The outer lift b of the heel has a central opening z through it of less diameter than said chamber o in order to form an inwardly-projecting collar or flange at the outer end of said chamber for retaining the hereinafter-described spring devices therein. The said spring devices constitute improved elements in the heel, which extend outwardly beyond the surface of the latter and first receive the force of the step of the wearer of the shoe, and, gradually yielding thereunder, allow the heel itself to move gradually against the ground, walk, or floor, thus preventing the wearying disagreeable effect of suddenly striking the heels thereagainst in walking. Said spring devices are also especially adapted for use in the heels of shoes worn by railroad train-hands and motormen on electric street-railway cars for relieving them from the ill-effects of the rigid jarring of the platforms of moving cars and the weariness of standing for a long time (as in the case of said motormen) on said platforms. Said spring devices

consist of a properly formed and tempered coil-spring d, preferably of conical form, as shown, which is placed in said chamber c in the heel A in the position shown in Fig. 1—that is, with its base against the upper wall of said recess. Having so placed said spring d, a buffer e, of rubber or analogous resilient material, is placed in the heel in the position shown in Fig. 1. Said buffer may have the border projections f thereon (shown in Figs. 1, 2, and 3) for engagement with the inner side of said collar k on the heel-lift b, whereby it is retained in operative connection with the heel A, or it may contain a surrounding-flange h, as shown in Fig. 4. Said projections f, however, are preferable as being more conveniently entered within said recess when the buffer is attached to said heel. Said buffer is also provided with a concave socket o to receive the smaller end of the said spring d, and it normally projects beyond the surface of the heel.

If occasion demands the retirement of the spring d from the socket in the heel, that is accomplished by pressing the projection bearing opposite sides of the buffer e toward each other, thereby moving each projection f toward the other and within the borders of the opening z in the heel-lift b and then withdrawing the buffer and the spring. The same manipulation of the buffer enables one to replace the buffer in the heel. Said concave socket in the buffer serves to hold the spring d in proper operative position in the heel-socket.

Having thus described my invention, what I claim, and desire to secure by Letters Patent, is—

The heel of a boot or shoe having a centrally-located chamber therein, and an outer lift for said heel having a perforation therethrough of less diameter than that of said chamber whereby an inwardly-projecting flange is formed around the outer end of said chamber combined with the coiled spring d, located in said chamber, and the buffer e, having the border projections f, f, for engagement with said flange, substantially as set forth.

ALVIN M. CUSHING.
